PHOTOTUBE CONTROL-TEMPERATURE INDICATING APPARATUS FOR FURNACES

Alan Warnick, Detroit, Mich., assignor, by mesne assignments, to The Ohio Crankshaft Company, Cleveland, Ohio, a corporation of Ohio

Application January 16, 1948; Serial No. 2,784

12 Claims. (Cl. 250—41.5)

1

This invention relates to phototube-controlled temperature indicating and power transmitting apparatus for furnaces and the like.

Among the objects of the invention are to provide a temperature indicator, readily applicable to induction furnaces, which is simple in construction, accurate in operation, adaptable to various types of furnaces and susceptible to assembly with utilization of light and readily obtainable equipment. An important object is to increase the stability of a circuit of the described type.

The invention involves the use of an electrical bridge arrangement which in use is initially balanced for a given preliminary furnace temperature condition and which subsequently is unbalanced on the development of heat in the furnace through the use of a light sensitive device, such as phototube and accessory circuits, the unbalance causing operation of power devices. The use of a bridge generally for this purpose is not new, the invention involving certain highly useful refinements, accomplishing the objects of the invention.

The drawings disclose:

In Figure 1, a wiring diagram of a preferred form of the invention; and

In Figures 2, 3 and 4, modifications of the invention.

Referring to Fig. 1, a source of direct current, supplying power to the circuit, is indicated by the numerals 10 and 11, 10 being the positive terminal. Connected in parallel with the conductors 12 and 13, extending respectively from terminals 10 and 11, are two branch circuits 14 and 15, forming the arms of the bridge. Branch circuit 14 includes two resistors 16 and 17, connected in series with a common junction point 18. Branch circuit 15 includes thermionic triodes 19 and 20, connected in series with each other and a group of resistors. Tube 19 is provided with an anode 21, directly connected to main conductor 12, grid 22 and cathode 23. Tube 20 is provided with an anode 24, a grid 25 and a cathode 26. The cathode 23 of tube 19 is connected to the anode 24 of tube 20 through a fixed resistor 27. The cathode 26 of tube 20 is connected to the main conductor 13 through a fixed resistor 28 and a variable resistor 29. The grid 25 of tube 20 is connected directly to conductor 13. The grid 22 of tube 19 is connected to a point 49 on conductor 32 intermediate the rheostat 36 and the anode 30 of the phototube 31. A capacitor 33 is connected between the grid conductor 32 and a point 34 in the conductor between resistor 27 and the anode 24 of tube 20. Point 34 is also connected to the grid-phototube conductor 32 through a variable resistor

2

or rheostat 36. The conductor 32 is provided with a shield 37 intermediate the rheostat and the phototube, which is grounded, as at 38. The cathode 39 of the phototube is connected to conductor 13, to the shield 37 and to ground 38.

The load branch 40 of the bridge connects point 18 in bridge circuit 14, and point 34 in bridge circuit 15. This branch includes a variable resistor 41, a meter 42, which may be calibrated to read directly in temperatures, and a relay coil 43, having a core 44 adapted when energized to actuate an armature 45 to open a switch 46 in the load circuit, including a source of power 47 and a load 48.

In the operation of the circuit, the bridge is initially balanced by means of the variable resistor 29 so that the current in the load bridge branch 40 is practically zero and the relay coil 43 is unable to actuate the armature 45 to break the load circuit. The rheostat 36, connected to the phototube, is adjusted for coarse sensitivity of the phototube effect on the bridge, and variable resistor 41, adjusted for fine sensitivity. The light sensitive element of the phototube 31 is positioned for reception of light from the furnace and this may be readily accomplished through the use of a light refractive tube, such as a quartz rod.

The effect of light impingement on the phototube cathode is to decrease the resistance of the phototube circuit, with a consequent modification of the bias on the grid 22 of tube 19 in such manner as to reduce the flow of current through the tube 19 and thus bring about a flow of current in the grid-bridge branch 40, sufficient to actuate the armature 45 and thus opening switch 46 in the load circuit. The effect of opening this switch may be to produce any desired effect, such as disconnection of the power source from the furnace where the apparatus is used in connection with an induction furnace. Simultaneously, the meter 42 may be read to obtain the approximate temperature developed at load actuation.

In the modification of the invention shown in Fig. 2, the phototube 31 is connected in series with the rheostat 36 between the anode of tube 19 at point 50 and the point 34 at the tube cathode. Grid 22 is connected to the point 51 intermediate the phototube and rheostat. In this arrangement also the shield 52, enclosing the cathode lead of the phototube between the tube and rheostat, is connected directly to the conductor 53 between point 50 and the phototube anode and grounded at 54.

The modification of Fig. 3 places the phototube 31 and rheostat 36 in series between bridge point 34 and point 55 in the conductor 13. The

conductor, joining the phototube and rheostat, is shielded, as at 57, and this shield, as well as the phototube anode 30, is grounded as at 58.

The modification of Fig. 4 is similar to that of Fig. 3 with the exception that the phototube anode is connected by conductor 59 to the anode of tube 19 at 50 instead of to bridge point 34. By this means, a larger potential drop through the phototube circuit is secured.

In all forms of the invention as disclosed, it is observed that the grid of the control tube is connected to a point, as 49, 51, 56 and 60, lying intermediate the phototube 31 and rheostat 36. Also in all forms, a capacitor 33 is connected to the control tube grid in parallel with the rheostat. Attention is directed to the fact that a ground connection of the phototube is made in each of the disclosed forms and that this ground connection is made to the lead-in conductor that is not directly connected to the grid of the control tube.

Certain important advantages result from the specific arrangements described hereinabove. The sensitivity of the apparatus is markedly improved through the use of the coarse and fine adjustment resistors 36 and 41, permitting adaptation to the requirements of any given furnace application. This sensitivity is augmented by practical elimination of stray field pickup through use of the grounded shield on conductor 32, connecting the phototube to the control grid of tube 19. In order further to develop the sensitivity of the apparatus, capacitor 33 is placed in parallel with the rheostat 36, whereby stray impulses not eliminated by the shield 31 may be filtered. By connecting the non-grid lead-in of the phototube directly to ground as shown in the various figures, the stability of the circuit is definitely increased.

Modifications other than described may be made, the invention being comprehended in the claims hereto appended.

What is claimed is:

1. An electrical circuit for temperature control comprising an electrical bridge circuit including two series resistors and two series vacuum tubes connected in series, one of said tubes being provided with grid and cathode elements, a current source connected to the respective junctions of each tube and the adjacent series resistor, and a load circuit between the junctions of the respective resistors and tubes, means in the bridge circuit for balancing the bridge at a selected temperature level, and means for unbalancing the bridge at another temperature level, said means comprising a phototube connected to said grid and in parallel with the other of said tubes, whereby variation of current in said phototube controls the voltage of the tube grid.

2. An electrical circuit for temperature control comprising an electrical bridge circuit including two series resistors and two series vacuum tubes connected in series, one of said tubes being provided with grid and cathode elements, a current source connected to the respective junctions of each tube and the adjacent series resistor, and a load circuit between the junctions of the respective resistors and tubes, means in the bridge circuit for balancing the bridge at a selected temperature level, means for unbalancing the bridge at another temperature level comprising a phototube connected to said grid, a variable resistor connected between the grid and cathode of said tube for controlling the sensitivity of the phototube on the bridge balance, and a capacitor con-

nected between said tube grid and cathode for by-passing stray currents.

3. An electrical circuit for temperature control comprising an electrical bridge circuit including two series resistors and two series vacuum tubes connected in series, said tubes each having an anode, cathode and grid, a current source connected to the respective junctions of each tube and the adjacent series resistor, a load circuit between the junctions of the respective resistors and tubes, a phototube having an anode connected to the grid of one of said tubes and to the anode of the other of said tubes and a cathode connected to the cathode of the other of said tubes, and means for varying the sensitivity of said phototube.

4. An electrical circuit for temperature control comprising an electrical bridge circuit including two series resistors and two series vacuum tubes connected in series, said tubes each having an anode, cathode and grid, a current source connected to the respective junctions of each tube and the adjacent series resistor, a load circuit between the junctions of the respective resistors and tubes, a phototube having an anode connected to the grid of one of said tubes and to the anode of the other of said tubes and a cathode connected to the cathode of the other of said tubes, means for varying the sensitivity of said phototube, and means for shielding the grid connection of said phototube from stray voltage impulses.

5. An electrical circuit for temperature control comprising an electrical bridge circuit including two series resistors and two series vacuum tubes connected in series, each of said tubes being provided with an anode, cathode and grid, a current source connected to the respective junctions of each tube and the adjacent series resistor, a load circuit between the junctions of the respective resistors and tubes, means in the bridge circuit for balancing the bridge at a selected temperature level, a phototube having anode and cathode elements, a conductor intermediate one of said phototube elements and the grid of one of said tubes, and a grounded shield enclosing said conductor, the other of said phototube elements being connected to said grounded shield.

6. An electrical circuit for temperature control comprising an electrical 4-branch bridge circuit including two series resistors and two series vacuum tubes connected in series, one of said tubes being provided with grid and cathode elements, a current source connected to the respective junctions of each tube and the adjacent series resistor, and a load circuit between the junctions of the respective resistors and tubes, means in one branch of the bridge circuit for balancing the bridge at a selected temperature level, means for unbalancing the bridge at another temperature level including a phototube connected to said grid, a variable resistor connected between the grid and cathode of said one tube, and a variable resistor in said bridge load circuit, whereby the sensitivity of the phototube on the bridge balance may be controlled.

7. An electrical circuit for temperature control comprising an electrical bridge circuit including two series resistors and two series vacuum tubes connected in series, one of said tubes being provided with grid and cathode elements, a current source connected to the respective junctions of each tube and the adjacent series resistor, and a load circuit between the junctions of the respective resistors and tubes, means in the bridge cir-

cuit for balancing the bridge at a selected temperature level, means for unbalancing the bridge at another temperature level including a phototube connected to said grid, sensitivity means including a variable resistor connected between the grid and cathode of said one tube, and a variable resistor in said bridge load circuit, whereby the sensitivity of the phototube on the bridge balance may be controlled, and means for securing an initial balance of said bridge.

8. An electrical circuit for temperature control comprising an electrical bridge circuit including two series resistors and two series vacuum tubes connected in series, one of said tubes being provided with grid and cathode elements, a current source connected to the respective junctions of each tube and the adjacent series resistor, and a load circuit between the junctions of the respective resistors and tubes, means in the bridge circuit for balancing the bridge at a selected temperature level, and means for unbalancing the bridge at another temperature level, said unbalancing means comprising the phototube, circuit connections forming therewith a parallel circuit around the other of said tubes, and a conductor connection between said tube grid and an intermediate point on said parallel circuit.

9. An electrical circuit for temperature control comprising an electrical bridge circuit including two series resistors and two series vacuum tubes connected in series, one of said tubes being provided with grid and cathode elements, a current source connected to the respective junctions of each tube and the adjacent series resistor, and a load circuit between the junctions of the respective resistors and tubes, means in the bridge circuit for balancing the bridge at a selected temperature level, and means for unbalancing the bridge at another temperature level, said unbalancing means comprising the phototube, circuit connections forming therewith a parallel circuit around the other of said tubes, and a conductor connection between said tube grid and an intermediate point on said parallel circuit, the phototube connection other than that connected to said grid being grounded.

10. An electrical circuit for temperature control comprising a source of direct current, a bridge network connected across said source for supply of power therefrom, means for balancing said bridge at a given temperature level, and means for unbalancing said bridge at another temperature level, said bridge comprising four resistors connected across said source in two parallel paths, each including two of said resistors in series, bridge-output points between the junctions of each pair of resistors, and power mechanism connected to bridge output points, and said unbal-

ancing means comprising a phototube, circuit means for connecting the phototube in parallel with one of said bridge resistors, and means electrically connected between said phototube circuit and another of said bridge resistors for varying the resistance of said other resistor in accordance with the current flow in said phototube circuit.

11. An electrical circuit for temperature control comprising a source of direct current, a bridge network connected across said source for supply of power therefrom, means for balancing said bridge at a given temperature level, means for unbalancing said bridge at another temperature level, and sensitive means for varying the sensitivity of said unbalancing means, said bridge comprising four resistors connected across said source in two parallel paths, each including two of said resistors in series, bridge-output points between the junctions of each pair of resistors, and power mechanism connected to bridge output points, said unbalancing means comprising a phototube, circuit means for connecting the phototube in parallel with one of said bridge resistors, and means electrically connected between said phototube circuit and another of said bridge resistors for varying the resistance of said other resistor in accordance with the current flow in said phototube circuit, and said sensitivity means comprising a variable resistor connected in series with said phototube.

12. An electrical circuit for temperature control comprising a source of direct current, a bridge network connected across said source for supply of power therefrom, means for balancing said bridge at a given temperature level, means for unbalancing said bridge at another temperature level, and sensitive means for varying the sensitivity of said unbalancing means, said bridge comprising four resistors connected across said source in two parallel paths, each including two of said resistors in series, bridge-output points between the junctions of each pair of resistors, and power mechanism connected to bridge output points, said unbalancing means comprising a phototube, circuit means for connecting the phototube in parallel with one of said bridge resistors, and means electrically connected between said phototube circuit and another of said bridge resistors for varying the resistance of said other resistor in accordance with the current flow in said phototube circuit, and said sensitivity means comprising a variable resistor connected in series with said phototube, and a second variable resistor connected between said bridge output points in series with said power mechanism.
